(57) **CLAIM**

The ornamental design for an adjustable safety helmet, as shown and described.

DESCRIPTION

FIG. 1 is a top, front and right-side perspective view of an adjustable safety helmet showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear view thereof in an open position;

FIG. 9 is a bottom plan view thereof in an open position; and,

FIG. 10 is a top plan view thereof in an open position. The details shown in broken lines form no part of the claimed design.
